FINGER CONTROL ATTACHMENT WRENCH

Herman Buford Evans, United States Navy

Application September 7, 1951, Serial No. 245,623

2 Claims. (Cl. 81—53)

(Granted under Title 35, U. S. Code (1952),
sec. 266)

1

The present invention relates to an improved tool particularly adapted for reaching and removing relatively inaccessible threaded objects.

An object of the invention is to provide a tool having a main body or stem to which may be pivotally attached a plurality of different sizes and patterns of wrench or jaw members.

Another object of the present invention is to furnish means for quickly connecting and disconnecting the various wrench members and the body members so that a minimum of time is used in replacing one wrench size or pattern with another.

Still another object is the provision of a hand grip mounted on one end of the stem and a pair of finger control rings positioned adjacent thereto, said control rings being connected by flexible cable to said wrench means. Pivotal movement of the wrench means for varying the angle thereof with respect to the stem occurs upon manipulation of the control rings by the operator.

Further objects and advantages of the invention will be apparent from the following description taken with the accompanying drawing in which:

Fig. 1 is a plan view of the present invention;

Fig. 2 is a side elevation of the wrench;

Fig. 3 is a sectional view taken on line 3—3 of Fig. 2;

Fig. 4 is an elevation of the means provided for attaching the body member to the wrench means with the latter in position for removal or connection;

Fig. 5 is a view similar to Fig. 4 showing the parts connected together;

Fig. 6 is a view similar to Figs. 4 and 5 showing the parts in locked assembled relation.

Similar reference characters represent similar parts throughout the drawings.

In working on engines in general, and more particularly those of the aircraft type, numerous parts secured by bolt and nut means or bolt means alone are relatively inaccessible with ordinary tools. In order to remove one part of the engine for repair it may be necessary to remove several other parts. Many times this is due to the lack of a tool which is capable of reaching the bolts and nuts which secure the part to the engine. For example, removal of the propeller governor requires the initial removal of the magneto, and the starter or generator cannot be removed without removing each other. The exhaust stack is an example of another part which is quite inaccessible. The present wrench has been devised to permit the mechanic to have ready

access to these parts so as to require only a small part of the time ordinarily used in removing them.

Referring now to the drawings, a main body or stem 10 is provided, there being a cross-piece in the form of a handle 11 secured to one end thereof. While the stem is shown to be of rectangular configuration, it is apparent that other shapes could be used. The other end of the stem is recessed to provide a shoulder 12 and a land 13. A pivot pin 14 is secured to the land in a position spaced from shoulder 12, said pin projecting slightly above the surface of the stem.

The wrench 15 which I have shown is of the open-end type having jaws 16 and a shank 17. The free end of shank 17 has an aperture 18 fashioned therein which is adapted to slidably receive pin 14 for pivotal movement.

The locking means which I utilize to maintain the connection between wrench 15 and stem 10 will now be described. As will be seen stem 10 has a generally flat surface on the upper side thereof. An elongated strip of spring metal, illustrated by numeral 19, is mounted in juxtaposed relation to said surface and is secured to the stem by rivets 20. One end of strip 19, illustrated as 19a, is skewed with respect to the strip, as shown in Fig. 4. Thus the end of shank 17 is permitted to enter between end 19a and stem 10 so that pin 14 may be received by aperture 18, as seen in Fig. 5. A ring 21 which encompasses stem 10 and strip 19 is slidably mounted with respect thereto. By sliding the ring toward the recessed end of the stem, end 19a is yieldingly moved into contact with the stem until an aperture 22 is received by pin 14, as shown in Fig. 6. Thus, wrench 15 is secured to stem 10 for pivotal movement with respect thereto in a manner permitting easy and quick removal should a different size or type of wrench be desired. It will be understood, of course, that wrench 15 could be of various other designs depending upon the need. For example, a ratchet type socket wrench could be substituted.

The pivotal movement of the wrench is controlled by the operator's fingers. The relative inaccessibility of the many parts of an engine make this control necessary. Sleeves 23 and 24 are secured to opposite sides of the stem by suitable means so that the sleeves extend longitudinally thereof. Flexible cables 25 and 26 are slidably received by said sleeves which act as guides therefor. One end of cable 25 is connected to ear 27 through detachable coupling ring 28 which is received by eyelet 29. One end of cable

26 is similarly connected to ear 30 through ring 31 which is received by eyelet 32. The opposite ends of cables 25 and 26 are connected to finger control rings 33 and 34 respectively. Thus the operator places his hand on the handle and two fingers in the rings provided. By first pulling on one cable and then the other the angular relation between the wrench shank and the body member is varied.

The use of this wrench for reaching relatively inaccessible bolts and nuts has greatly reduced the time necessary for removing various engine parts. As stated heretofore many parts may now be removed without removing other parts which ordinarily had to be removed. The detachable coupling provided between the wrench and the stem makes for quick changing from one size or type of wrench to another. By placing the hand on handle 11 and grasping rings 33 and 34 with the fingers, jaws 16 may readily be placed in position on the bolt or nut to be removed.

While I have disclosed a specific embodiment of the invention it will be realized that various modifications thereof could be made without departing from the spirit and scope of the invention, as defined in the appended claims.

The invention described herein may be manufactured and used by or for the Government of the United States of America for governmental purposes without the payment of any royalties thereon or therefor.

I claim:

1. A tool for removing threaded objects in relatively inaccessible places comprising an elongated body member, wrench means, means detachably securing said wrench means to one end of said body member for pivotal movement, and means including a flexible cable connected to said wrench means for controlling the pivotal movement thereof, said detachable securing means including a pivot pin mounted on said one end of said body member, said wrench means having an aperture therein for receiving said pivot pin, a resilient strip mounted on said body member with a free end extending over but flexed from said one end

45

5 of said body member and having an aperture in said free end adapted to receive the end of said pivot pin when the strip end and body member are moved adjacent each other, and means surrounding a portion of said strip and said body member for maintaining them in said adjacent relation.

2. A tool for removing threaded objects in relatively inaccessible places comprising an elongated body member, wrench means, means detachably securing said wrench means to one end of said body member for pivotal movement, said detachable securing means including a pivot pin mounted on said one end of said body member, said wrench means having an aperture therein for receiving said pivot pin, a resilient strip mounted on said body member with a free end extending over but flexed from said one end of said body member and having an aperture in said free end adapted to receive the end of said pivot pin when the strip end and body member are moved adjacent each other, and means surrounding a portion of said strip and said body member for maintaining them in said adjacent relation.

HERMAN BUFORD EVANS.
